UNITED STATES PATENT OFFICE

2,635,272

COMBINED MOP FOR CLEANING BOWLING ALLEY BEDS AND GUTTERS

Robert H. Johnson, Kansas City, Mo.

Application September 30, 1948, Serial No. 52,022

1 Claim. (Cl. 15—118)

1

This invention relates to a cleaning device and more particularly to a device for cleaning bowling alley beds and gutters.

It is essential to keep bowling alley beds and gutters clean at all times to increase life of the shellac or lacquer placed upon their surfaces which is usually several times a season. Heretofore, it has been necessary to use a different tool for cleaning the gutter than the bed, thus entailing more expense and also not assuring proper cleaning of the gutters. For instance, if the bed is cleaned and polished dirt will be left in the gutters, and when the gutters are clean, a certain amount of dirt and dust will be returned to the bed along the edges of the gutters.

It is, therefore, the principal object of the present invention to provide a device for sweeping both the bed and gutters of bowling alleys in one sweeping operation.

Other objects of the present invention are to provide a device of this character having a frame upon which a mop head may be carried for cleaning the bed of the alley and attachments on each end of the frame for mop heads transversely of the main mop head for cleaning the gutters; to provide a device of this character which may be utilized for cleaning the bed alone or the gutters alone or both in combination and providing means for quick assembly and disassembly of the gutter pieces to the bed or frame pieces; and to provide a device of this character simple, economical to manufacture, and efficient in operation.

In accomplishing these and other objects of the present invention, I have provided improved details of structure, the preferred forms of which are illustrated in the accompanying drawings wherein:

Fig. 1 is a perspective view of my cleaning device showing a fragmentation of the handle member.

Fig. 2 is a longitudinal central section through a part of a mop head and gutter head of the device.

Fig. 3 is a perspective view of the main and gutter heads of my invention, the parts being shown in disassembled relation.

Referring more in detail to the drawings:

I designates a cleaning device embodying the features of my invention, comprising a frame 2 consisting of an elongated block 3 of wood, metal or the like, having upstanding screw-threaded spaced shanks of bolts 4 and 5. The block 3 is of a length slightly shorter than the width of the bed 6 of a bowling alley usually approximately 42

inches. A metallic strap 7 is provided having spaced openings 8 adapted to engage over the threaded shanks 4 and 5, the strap 7 being longer than the block 3 and of a length substantially equal to the distance between the gutters of a bowling alley. The respective ends of the strap 7 are offset or turned downwardly from the block 3 for a purpose later described.

A bail 9 is provided to accommodate a handle 10 for securing the handle to the frame. The bail consists of a single strand of wire of sufficient length to withstand ordinary strains in mops of this character and is formed by bending upon itself in substantially the center thereof to form an eye 11 through which the handle can extend. The side arms 12 and 13 of the bail are coiled to form eyes 14 and 15 for engaging the bolts 4 and 5 on the block 3. A second bail 16 is provided comprising a wire bent upon itself as indicated at 17 and extends through an opening in the handle as indicated at 18 as is conventional practice, the arms 19 and 20 of the bail 16 also being provided with eyes for engaging the bolts 4 and 5. A ring 21 is provided for engaging over the wire and the end of the handle as indicated at 22 to retain the wire in engagement with the handle member. The eyes of the bails are adapted to engage the bolts 4 and 5 and be held in rigid relation thereto by thumb nuts 23.

With the device constructed and assembled as thus far described, the frame member 2, strap 7 and handle will be held in rigid relation, one to the other. A mop head or wiping element 24 formed of strings 25 sewed to a canvas member 26 is tied to the frame 2 by suitable means such as strings or ties 27, said wiping element extending around the ends of the block 3. The strings of the wiping element 24 are of such length that those adjacent the ends of the block 3 extend into the adjacent edge of the gutter portions of the alley. With the construction thus far described, the bed portion 6 of the bowling alley may be cleaned.

When it is desired to clean both the bed portion 6 and gutter portions 28, I provide sub-blocks 29 and 30, here shown to be elongated and transversely of the main block. The sub-block members are adapted to be held to the outer ends of the strap 7 by screws or the like 31 extending through openings 32 in the respective ends of the strip and engaged in substantially the center of the sub-block members 29 and 30. Mops 33 and 34 are provided for the sub-block members 29 and 30, formed of string and canvas as with

the main mop head and fastened to the sub-block members by ties or the like 35, said mops extending around the ends of the sub-block members 29 and 30. The offset portions 36 and 37 of the strap 3 will allow the transverse sub-blocks 29 and 30 to extend below the main head and thus engage the bottom of the gutters 28.

It will be obvious from the foregoing that I have provided an improved cleaning device for bowling alleys having a plurality of brushing surfaces for cleaning both the bed and gutters of the bowling alley or with which the gutters or beds may be cleaned independently one of the other.

What I claim and desire to secure by Letters Patent is:

A cleaning device for bowling alleys having bed and gutter portions comprising, a frame including a main block, said block being slightly shorter than the width of said bed, a wiping element removably secured on the main block and extending around the ends of same, said wiping element including a plurality of strings throughout the length thereof with the strings adjacent the ends of the main block of a length to extend into the edge of the gutter portion, an elongated strap member arranged longitudinally of the main block and extending outwardly from each end of said main block, fastening means spaced from the ends of the main block removably mounting the strap member on the upper face of the main block, the ends of said strap member being offset downwardly and outwardly forming

ing arms over said gutter portions, a handle, a bail on the handle adjacent one end thereof, said block having spaced bolt shanks extending from its upper face, said strap member having openings aligning with said shanks, said bail having spaced eyes thereon through which said shanks extend, means on said shanks for securing the bail to the main block to connect the handle thereto, sub-blocks removably carried by the arms of the offset portions of said strap member transversely of the main block and adapted to extend into the gutters on the respective sides of the alley bed, and wiping elements including a plurality of strings removably secured on said sub-blocks.

ROBERT H. JOHNSON.
